J. A. Rutherford
Robert Everett,

UNITED STATES PATENT OFFICE.

JOHN B. SEEL, OF CLINTON VILLAS, CHURCH ROAD, URMSTON, COUNTY OF LANCASTER, ENGLAND.

UMBRELLA OR PARASOL.

SPECIFICATION forming part of Letters Patent No. 284,495, dated September 4, 1883.

Application filed May 11, 1883. (No model.) Patented in England October 16, 1882, No. 4,914.

To all whom it may concern:

Be it known that I, JOHN BUCKLEY SEEL, a subject of the Queen of Great Britain, residing at Clinton Villas, Church Road, Urmston, in the county of Lancaster, England, manager to umbrella-manufacturers, have invented certain new and useful Improvements in Umbrellas and Parasols, (for which I have obtained a patent in Great Britain, No. 4,914, bearing date October 16, 1882,) of which the following is a specification.

My invention consists in attaching the covering of umbrellas or parasols to the ribs by inserting the seams of the gores or cords or wires, sewed or otherwise attached to such seams, into tubular cavities in the ribs themselves. I use metal ribs of a tubular form, with a longitudinal slit along the outer edge of each rib. Tubular ribs of this character are usually and best made of steel, are properly tempered, and are not new, except so far as the position and use of the longitudinal slit is concerned, that slit having usually been placed either on the inner or one of the side edges, and not being made use of. The form and material of the rib and position of the slit, however, I do not claim as part of my invention.

In the drawings accompanying this specification, A is the tubular-rib, having a longitudinal slit, B, on its outer side. At the end of the rib which is attached to the stick of the umbrella or parasol I widen out the slit into a boat-shaped cavity, C. (Shown in Figure 1, and partly in Fig. 2.) This boat-shaped cavity may be formed at either end of the rib; but I prefer to have it at the end which is to be attached to the stick.

Fig. 3 shows the mode in which the tip is formed, the part D being flattened and perforated to receive the stitches which fasten the ends of the gores of the covering. As I require the longitudinal slit to be open the whole length of the rib, (except where the rib is flattened for attaching to the notch, and at the tip,) I use a new form of "get" or middle bit, E, which is shown in Figs. 4 and 5. I

prefer to make it of brass, and to tip the stretcher also with brass, so as to avoid, as much as possible, any rusting at this point. 50. This get or middle bit is formed with a groove in its upper edge, as shown in transverse section in Fig. 6, for the reception of the rib, upon which it is pressed together, so as to hold the rib, and yet not close the slit in the 55 rib. I do not, however, claim the form of the get or middle bit, or its mode of attachment, as part of my invention.

I either roll over the edges of the gores of the covering and stitch or otherwise attach 60 them together, so as to make a cord or ridge on the inner side of the seam, or I stitch a cord or wire into or otherwise attach it to the edges of each seam. I then insert that cord, 65 ridge, or wire into the boat-shaped cavity C 65 in the end of the tubular-rib and draw it through the whole length of each rib, (except such part of such rib at each end of the rib as is required for the formation of the tip, and of the attachment to the notch at the apex 70 of the umbrella or parasol,) or, instead of inserting the cord, ridge, or wire into the rib at one end and drawing it through, the rib may be sprung open, so as to allow the cord, ridge, 75 or wire to be inserted through the slit in the rib, which will then, by its own elasticity, close up again; but the rib can be made of stouter material when the cord, ridge, or wire is to be drawn through than if it is to be sprung in, and for that and other reasons the 80 mode of drawing it through the rib is the best. I make the cord, ridge, or wire so thick as not to pass through the slit in the upper side of the rib, (unless sprung open for the purpose,) and to fit tightly inside the tube. The seam 85 between the gores is thus securely held in the rib.

Fig. 7 shows a transverse section of the rib, in which F is a cord or wire sewed into the seam, and G G the umbrella-covering. The 90 ridge formed by rolling over the edges of the gores and stitching them together is not shown in this figure, but would occupy the same space as the cord or wire. I do not

claim as part of my invention the mode of forming or attaching to the seams of the gores the said ridge, cord, or wire.

What I claim as my invention is—

5 In an umbrella or parasol, the gore-covering provided with a ridge, cord, or wire along its seam, in combination with a rib formed with a tubular cavity, into which the ridge, cord, or wire is fitted, substantially as and for 10 the purpose set forth.

In witness whereof I have hereto set my hand this 25th day of April, 1883.

JOHN BUCKLEY SEEL.
